(57) **CLAIM**

The ornamental design for a rotor element for a shear valve assembly, as shown and described.

DESCRIPTION

FIG. 1 is an exploded top perspective view of a rotor element for a shear valve assembly showing out new design; and, FIG. 2 is a top plan view thereof.

The phantom lines shown in FIG. 1 represent the longitudinal axis of rotation.

The broken lines showing the body of the rotor element and a stator element of the shear valve assembly are for illustrative purposes only and form no part of the claimed design.
